UNITED STATES PATENT OFFICE.

NORMAN C. NICOL, OF BUFFALO, NEW YORK, ASSIGNOR TO THE BERBECKER & ROWLAND MFG. CO., OF WATERVILLE, CONNECTICUT, A CORPORATION OF CONNECTICUT.

SUPPORT.

1,281,061.

Specification of Letters Patent.

Patented Oct. 8, 1918.

Application filed November 21, 1917. Serial No. 203,167.

To all whom it may concern:

Be it known that I, NORMAN C. NICOL, a citizen of the United States of America, residing in Buffalo, in the county of Erie and State of New York, have invented certain new and useful Improvements in Supports, of which the following is a specification.

This invention relates to supports for parts separable from one another, such as boxes, trunks, casings, etc., provided with lids or covers, or the like, and aims to provide improvements therein, and is an improvement for certain purposes on the construction shown in my application for Letters Patent of the United States, filed May 26, 1915, Serial No. 30,523.

In my said application there is disclosed a device or means, whereby the supporting elements, when the lid or cover is raised, will automatically lock the same in such position, and by a further movement of the lid or cover the lock will be released and prevented from reengaging while the lid is approaching the body. This operation of the device takes place without requiring any special care or refinements of manipulation on the part of the user.

In said application the broad idea of invention contemplates a construction wherein the guard partakes of substantially the same degree of movement as the relative movement between the prop and lock, or wherein the guard partakes of a substantially less amount of movement. The present invention is especially directed to that part of the broad idea of invention wherein the guard has but limited movement on the prop. This construction is of especial importance and advantage in connection with supports of plated or polished metal wherein wearing off or scratching of the surfaces of the metal, by reason of extensive movement of the guard on the prop, is desired to be avoided.

An embodiment of the invention is illustrated in the accompanying drawing, wherein—

Figure 1 illustrates a vertical cross-section of a box having the invention applied thereto;

Fig. 2 is an enlarged detail view of the prop and guard in the position of the parts shown in Fig. 1;

Figs. 3-5 inclusive, are views similar to

Fig. 2, illustrating the prop and guard in different operative positions, and

Figs. 6 and 7 are detail views of the guard.

In said drawings, wherein the support is illustrated as applied to a box, numeral 1 designates a box, 2 its cover, and 3 the support. Numeral 4 designates the prop, and 5 the guard. The guard is provided with an irregular opening 13 therein, and is fitted upon the prop in such manner that it may slide thereon with slight friction, to this end being conveniently provided with curled edge portions 16 fitting around the edges of the prop. See Figs. 6 and 7. The prop is attached to the cover, as by the pin 7 or screw 6 passing through a hole in the prop and fastening into the cover.

7 designates a locking pin fixed upon the box. This locking pin 7 passes through a slot 8 provided in the prop, and is adapted to fit within a recess 9 for holding the cover and box in open or separated position.

When the cover is lifted the locking pin 7 slides in the slot 8 in the prop until it strikes a projection 10. This projection 10 forces the locking pin 7 to assume a position against a part of the wall 11 of the recess 9. The guard 5 has thereon a projection 12, between which projection 12 and the wall 11 the locking pin 7 becomes jammed or stopped. This prevents further opening movement of the cover 2. By simply dropping or lowering the cover after the opening movement has been arrested, as just described, the locking pin 7 falls within the recess 9, as indicated in Fig. 4, and the cover is thereby securely supported.

The guard 5 has a part 14 (Fig. 3) which strikes against the pin 7 as the pin enters the recess 9, which contact with the pin 9 causes the guard to be slid to a slight extent upon the prop, thereby raising the projection 12 on the prop to a position (Fig. 4) where the locking pin 7 will pass between said projection and the wall part 11 of the recess.

To move the cover on the box to closed position, the support being in the position shown in Fig. 4, the cover is lifted, the locking pin 7 passing into the recess 15 at the lower end of the slot 8 in the prop 4. This passage of the pin 7 is permitted by the guard 5, inasmuch as the projection 12 on

the guard has been raised to a position which permits the locking pin 7 to pass between said projection 12 and the projection 11 on the prop.

- 5 When the locking pin 7 strikes the wall 17 of the lower part of the opening 13 in the guard, the guard is slid upon the prop until the pin 7 comes in contact with the wall 18 at the lower side of the recess 15 in the 10 prop. The parts will now be in the position shown in Fig. 5. When the guard is slid to its lowermost position, a part 19 is moved into position to cover the entrance to the locking recess 9.
- 15 When the cover is now moved to closing position, the pin 7 passes around the projection 12 upon the guard, and the projection 10 upon the prop and is prevented from entering the locking recess by the part 19 20 of the guard. The pin then comes in contact with a shoulder 20 upon the guard, and during a succeeding part of the closing movement of the lid the guard 5 is slid upon the prop. The slot 8 has a curved wall 22, 25 somewhat above the locking recess 9, and this curved wall of the slot 8 acts to move the prop relatively to the pin 7 in such manner that the pin moves from behind the shoulder 20 upon the guard. When the pin 30 7 moves from behind the shoulder 20, the pin 7 is free to move in the slot 8 without carrying with it the guard 5. The relative position of the parts at this stage of the closing of the cover is shown in Fig. 2. The 35 movement of the guard by the action of the pin 7 against the shoulder 20 at the same time carries the part 19 out of position to obstruct the entrance to the locking recess 9 and brings the projection 12 of the guard 40 in position to coöperate with the part 10 of the prop in throwing the prop in such manner that when the cover is again lifted the pin strikes the projecting part 11 upon the prop, and becomes held thereagainst by the 45 coöperation of the projection 12 upon the guard.
- The operation of the device will be understood from the foregoing description.
- It will be seen that the movement of the 50 guard 5 upon the prop 4 is, or can be made to be, very slight, in such manner that scratching or wearing of a plated or polished prop, except a small portion near its end, is avoided.
- 55 Moreover, it will be seen that the separable part, as the cover, is definitely stopped at a position where the locking pin 7 is adjacent the locking recess, and certainly falls within the locking recess when the lid 60 is released. Thereupon the cover may be closed by simply lifting the cover slightly and closing it, the locking recess being obstructed in such manner that no care of manipulation is necessary in order to prevent 65 the locking pin entering the locking

recess, and the cover may move to closed position in a simple and ordinary manner.

The inventive ideas may receive other mechanical expressions than those herein specifically illustrated and described, and the subject of the invention may be applied to separable parts generally. 70

What I claim is:

1. A support for separable parts such as a box and its cover, comprising a prop and a guard, and a locking pin, said guard being 75 slideable longitudinally of said prop and being considerably shorter than said prop, said pin being movable beyond said guard, said prop having a locking recess, said guard having a part adapted to cover and uncover said locking recess and being moved by said pin, and means for disengaging said pin and guard, whereby said guard has but limited movement with respect to said prop. 80

2. A support for separable parts such as a box and its cover, comprising a prop and a guard, and a locking pin, said prop having a locking recess, said guard having a part adapted to cover and uncover said locking 90 recess and being moved by said pin, means for disengaging said pin and guard, whereby said guard has but limited movement with respect to said prop, said prop having a recess below said locking recess, said guard 95 having a projection coöoperating with a wall of said prop for engaging said pin on opening movement of the separable parts to stop further open movement of the parts and prevent said pin entering said lower recess, and a part on said guard making contact with said pin when the pin enters said locking recess for moving said guard to a position where said projection thereon 100 is out of position to coöperate with said projection on the prop in preventing passage of the pin into said lower recess. 105

3. A support for separable parts such as a box and its cover, comprising a prop and a guard, and a locking pin, said prop having a locking recess, said guard having a part adapted to cover and uncover said locking recess and being moved by said pin, means for disengaging said pin and guard, whereby said guard has but limited movement with respect to said prop, said prop having a recess below said locking recess, said guard having a projection coöoperating with a wall of said prop for engaging said pin on opening movement of the separable 110 parts to stop further opening movement of the parts and prevent said pin entering said lower recess, a part on said guard making contact with said pin when the pin enters said locking recess for moving said guard to 115 a position where said projection thereon is out of position to coöperate with said projection on the prop in preventing passage of the pin into said lower recess, and a part on said guard making contact with said 120

125

130

pin when the pin is in the lower recess in the prop for moving said covering part on said guard over said locking recess.

4. A support for separable parts such as 5 a box and its cover, comprising a prop and a guard, and a locking pin, said prop having a locking recess, said guard having a part adapted to cover and uncover said locking recess and being moved by said pin, 10 means for disengaging said pin and guard, whereby said guard has but limited movement with respect to said prop, said prop having a recess below said locking recess, said guard having a projection coöperating 15 with a wall of said prop for engaging said pin on opening movement of the separable parts to stop further opening movement of the parts and prevent said pin entering said lower recess, a part on said guard making 20 contact with said pin when the pin enters said locking recess for moving said guard to a position where said projection thereon is out of position to coöperate with said projection on the prop in preventing passage of 25 the pin into said lower recess, and a part on said guard making contact with said pin when the pin is in the lower recess in the prop for moving said covering part on said guard over said locking recess, said guard 30 having a shoulder thereon, brought by said latter movement into position to contact with said pin upon closing movement of said separable parts, whereby said guard may be moved when said pin contacts with said 35 shoulder to a position where the covering part on the guard uncovers said locking recess.
5. A support for separable parts such as a box and its cover, comprising a prop and 40 a guard, and a locking pin, said prop having a locking recess, said guard having a part adapted to cover and uncover said locking recess and being moved by said pin, said prop having a recess below said locking recess, said guard having a projection coöperating 45 with a wall of said prop for engaging said pin on opening movement of the separable parts to stop further opening movement of the parts and prevent said pin entering said lower recess, a part on said guard making 50 contact with said pin when the pin enters said locking recess for moving said guard to a position where said projection thereon is out of position to coöperate with said projection on the prop in preventing 55 passage of the pin into said lower recess, a part on said guard making contact with said pin when the pin is in the lower recess in the prop for moving said covering part on said guard over said locking recess, said 60 guard having a shoulder thereon, brought by said latter movement into position to contact with said pin upon closing movement of said separable parts, whereby said guard may be moved when said pin contacts with said 65 shoulder to a position where the covering part on the guard uncovers said locking recess, and a part on said prop for moving said pin from engagement with said shoulder. 70
6. A support for separable parts, such as a box and its cover, comprising a prop and a guard, and a locking pin, said prop having a slot therein with a turn therein in which said pin slides, said prop having a locking 75 recess opening into said slot, said guard having a part adapted to cover and uncover said locking recess, and being moved by said pin, the wall of the prop at said turn acting to disengage said pin and guard, whereby said 80 guard has but limited movement with respect to said prop. 75

In witness whereof, I have hereunto signed my name.
